UNITED STATES PATENT OFFICE.

JAMES H. PROTHERO, OF CHICAGO, ILLINOIS.

DENTAL FACE-BOW.

No. 894,983.

Specification of Letters Patent.

Patented Aug. 4, 1908.

Application filed November 25, 1907. Serial No. 403,579.

To all whom it may concern:

Be it known that I, JAMES H. PROTHERO, a citizen of the United States, residing at Chicago, in the county of Cook and State of Illinois, have invented certain new and useful Improvements in Dental Face-Bows, of which the following is a specification.

My invention relates to improvements in dental face-bows such as are used by dentists 10 for registering the correct relation between the natural alveolar borders and condylar processes of the lower jaw in the living subject and is capable of adjustment to the occluding frame in such manner as to record 15 the same relation between the plaster models and frame hinges as was sustained by the natural alveolar borders to their condyles or hinges.

The especial object of my improvements is 20 to provide a dental face-bow having on each of its ends adjustable supporting means capable of universal movement and adapted to support the said face-bow while adjusting the contact rods over the outer ends of the 25 condyles and for holding said face-bow in position after it has been properly adjusted.

My improvements can be made a part of the dental face-bow by a proper modification of the cross head castings on each end of the 30 dental face-bow now in general use or they can be made in the form of separate attachments slidably mounted on the ends of the dental face-bow frame as herein described and shown in the drawings accompanying 35 this application.

In the drawing—Figure 1 is a top plan view of my improved dental face-bow; Fig. 2 a fragmentary view taken on the line 2—2 of Fig. 1; Fig. 3 a view of the underside of Fig. 2; 40 Fig. 4 a longitudinal sectional view of a fragment of my improvement comprising, an ear tip, supporting rod with its sleeve and coil spring. Fig. 5 a perspective view of that portion of the dental face-bow which I claim 45 as my improvement; and Fig. 6 an elevation view of a fragment of the dental face-bow.

Referring to the drawing in detail—the reference numeral 7 represents a U-shaped frame made preferably from a steel rod or tube. Slidably arranged on the central portion of the said frame is a universal clamp 8 having an opening 9 to receive and hold a trial plate support 10. Secured on each end of the said frame is a cross head or bearing 11 having a threaded slotted end to receive the clamping nut 12. Arranged in each of said

bearings is a contact rod 13 provided on its inner end with a head 14 for engaging the condyles. Each of the rods 13 is longitudinally adjustable as indicated by the dotted 60 lines 13^a, Fig. 3.

The mechanism, as described above in detail, is of the character in general use and forms no part of my invention proper which latter consists of two separate adjusting and supporting means or mechanisms 65 slidably mounted on the ends of the frame 7. In said adjusting and supporting means 15 indicates a sleeve slidably mounted on the frame 7, and carrying a set screw 16 for 70 engagement with said sleeve, and provided with a slot to receive the pin 17 projecting from the frame, and having at one end two perforated projections 18, and having at its opposite end two guides 19. Arranged between said guides is an arm 20 carrying a set screw 21 for engagement with the sleeve 15, and having one end hinged between the projections 18, and carrying on its opposite end a sleeve 22 having in one end a removable tubular nut 23. Slidably arranged in each of said sleeves is a supporting rod 24 having an annular collar 26 for engagement with the nut 23, and provided on its inner end with a hollow ear tip 25 of suitable 80 shape for fitting into the external ear and perforated so that when adjusted it will not interfere with the hearing of the living subject. Surrounding each of the rods 24 between said collar and the opposite end 90 of the sleeve is a spiral spring 27 adapted to keep the ear tips 25 in place when inserted in the ears.

The longitudinal adjustment of the rods 24 as indicated by the dotted lines 24^a in 95 Fig. 3; the vertical adjustment of the ear tips 25 as indicated by the dotted lines 25^a in Fig. 2; and the longitudinal movement of the sleeves 15 as indicated by the dotted lines 15^a in Fig. 1 permits a back and forward, a vertical and a side to side movement of the dental face-bow thereby permitting the contact rods to be accurately adjusted to the condyle ends and in which position it is firmly supported by means of the ear 105 tips 25 resting in the ears.

Having thus described my invention what I claim as new and desire to secure by Letters Patent, is—

1. A dental face-bow provided at each 110 end with a contact rod and a supporting rod.

2. A dental face-bow provided at each end with a contact rod and a supporting rod, the latter being slidably connected with the face-bow and having a vertical and longitudinal adjustment.
3. The combination with a dental face-bow having adjustable contact rods, of adjustable supporting rods adjustably connected with the ends of the face-bow frame and having ear tips for fitting into the external opening in the ears.
4. A dental face-bow provided at each end with a longitudinally adjustable contact rod and a supporting rod slidably connected with the frame of the face-bow and having also a vertical and longitudinal movement.
5. In a face-bow of the character described, a U-shaped frame provided at each end with a cross head or bearing, contact rods adjustably mounted in said bear-

ings, sleeves slidably mounted on the ends of the said frame, arms hinged to said sleeves and carrying sleeves on their outer ends, supporting rods slidably arranged in 25 said sleeves and having their inner ends adapted to fit the external opening in the ears, and coil springs surrounding the supporting rods for the purpose set forth.

6. A dental face-bow provided at each 30 end with a longitudinally adjustable contact rod and a supporting rod having a vertical adjustment and two horizontal adjustments working at right angles to each other.

In testimony whereof I affix my signature in presence of two witnesses.

JAMES H. PROTHERO.
